MYRINGOTOMY KNIFE

David L. Walchle, Cincinnati, Ohio, assignor to Xomox Corporation, Cincinnati, Ohio

Filed Nov. 17, 1972, Ser. No. 307,582

Term of patent 14 years

Int. Cl. D24—02

U.S. Cl. D83—12 R

FIG. 1 is a perspective view of a myringotomy knife embodying my new design.

FIG. 2 is a side plan view thereof.

FIG. 3 is a plan view of the other side of FIG. 2.

FIG. 4 is a top plan view of FIG. 3.

FIG. 5 is a bottom plan view of FIG. 3.

FIG. 6 is an end elevational view of the left end of FIG. 1.

FIG. 7 is an end elevational view of the right end of FIG. 1.

I claim:

The ornamental design for a myringotomy knife, as shown and described.
